UNITED STATES PATENT OFFICE

163,374

SEMIRIMLESS SPECTACLE FRAME

Arthur Ditto, Roslindale, Mass., assignor, by
mesne assignments, to Marine Optical Manu-
facturing Co., Boston, Mass., a corporation of
Massachusetts

Application January 12, 1948, Serial No. 143,675

Term of patent 14 years

(Cl. D57—1)

To all whom it may concern:

Be it known that I, Arthur Ditto, a citizen of the United States, residing at Roslindale, State of Massachusetts, have invented a new, original, and ornamental Design for Semi-Rimless Spectacle Frame, of which the following is a specification, reference being had to the accompanying drawings, forming a part hereof.

In the accompanying drawings, Fig. 1 is a front elevation of a semi-rimless spectacle frame embodying the design of my invention; Fig. 2 is a plan of the same; and Fig. 3 is an end elevation.

The essential features of my design for the semi-rimless spectacle frame shown reside in lens-holding ears that extend integrally downwardly and inwardly from the respective temple-connecting end pieces, at an angle of approximately forty-five degrees, each toward the nose guard that is nearer thereto, but in the same

general direction as the direction of downward and outward extension of the nose guard that is farther therefrom, all as specifically illustrated.

I claim:

The ornamental design for a semi-rimless spectacle frame, substantially as shown and described.

ARTHUR DITTO.
